CAR TRUCK.

Application filed June 9, 1926. Serial No. 114,739.

This invention relates to trucks and, more particularly, to railway car trucks in which the capacity of the bolster springs is reinforced by additional spring units of shorter free height than the original spring units.

The principal object of our invention, generally considered, is the provision of additional springs for augmenting the capacity of the nest of springs supporting the truck bolster, said additional springs, however, being shorter and preferably stiffer than the original spring units whereby they are not brought into play until after a predetermined compression of said original spring units.

An object of our invention is the provision of a seven unit nest of springs for supporting each end of the truck bolster, said nest of springs comprising five spring units normally positioned with respect to one another and two additional springs positioned on opposite sides of the center spring unit of the five unit nest of springs and located substantially on the transverse or short center line of said five unit nest of springs, said additional springs being shorter than the units of the five unit nest of springs and adapted to come into play only after a predetermined compression of the five unit nest of springs, said additional springs, however, being preferably stiffer than the other springs and of approximately the same solid height.

A further object of our invention is the reinforcement of the nests of springs supporting the truck bolsters of railway car trucks, said reinforcement comprising additional spring units associated with the original units of the nest of springs and preferably of such a height that they just come into play when the original springs are normally loaded.

A still further object of our invention is the supporting of the bolster in a railway car truck by means of nests of springs each consisting of seven spring units hexagonally arranged with the seventh unit centrally positioned with respect to the other six units, two of said spring units disposed on opposite sides of the center spring unit being formed of thicker material than the remaining spring units of each nest of springs and of a shorter free height than said spring units whereby the capacity thereof is reserved until after a predetermined compression of said

other spring units, the tension member of the side frame underlying said nest of springs being substantially box shape in cross section and appropriately modified for efficiently supporting said nest of springs by 60 causing the side webs thereof to diverge outwardly until the upper ends thereof lie directly beneath the inner and outer spring units, respectively, of said nest of springs, that portion of the tension member of the 65 side frame, directly beneath the center spring unit, being reinforced by transverse webs extending inwardly from the side webs between the upper and lower webs of the side frame tension member. 70

Other objects and advantages of the invention relating to the particular arrangement and combination of the various parts will become apparent as the description proceeds. 75

Referring to the drawings illustrating our invention, the scope whereof is defined by the appended claims:

Figure 1 is a fragmentary side elevation, partly in section, of a railway car truck 80 particularly showing the bolster springs and the adjacent portions of the side frame, bolster and spring plank.

Figure 2 is a horizontal sectional view on the line 2-2 of Figure 1 looking in the direction of the arrows. 85

Figure 3 is a vertical sectional view on the line 3-3 of Figure 1 looking in the direction of the arrows.

Figure 4 is a diagrammatic plan view particularly illustrating the construction of the tension member of the side frame underlying the bolster springs which are indicated diagrammatically by dot and dash lines. 90

Figure 5 is a detailed top plan view of the 95 lower spring plate and is also a bottom plan view of the upper spring plate.

Figures 6, 7, 8 and 9 are views corresponding to Figures 1, 2, 3, and 4, respectively, but showing another embodiment of our invention. 100

Referring to the drawings in detail, like parts being designated by like reference characters and first, considering the embodiment or modification illustrated in Figures 1 to 5, inclusive, a side frame 1 is formed with a compression member 2, a tension member 3 and bolster guide columns or strut portions 4 spacing intermediate portions of said compression and tension mem- 105 110

bers and leaving a window or bolster opening 5 therebetween. The compression member 2 may be generally U shape in cross section and the strut portions 4, particularly 5 at the bolster guiding portions thereof, may be of similar construction. The tension member 3, particularly between the strut portions 4 beneath the window opening 5, is formed generally box shape in cross section 10 and provided with an upper web 6, a lower web 7, a front or outer web 8 and a rear or inner web 9. The lower web 7 is preferably substantially uniform in width while the upper web 6 is preferably increased in 15 width beneath the window opening to form a spring supporting or spring plank seat portion of the side frame 1. The outer and inner webs 8 and 9, respectively, preferably extend from the side edges of the lower web 20 7 directly upward to intermediate portions of the upper web 6 except directly beneath the bolster opening 5 where they are preferably sloped outwardly and upwardly so as to meet the upper web 6 substantially 25 directly beneath certain springs of the supported nest of springs, as will more clearly appear hereinafter.

Preferably supported directly on the spring plank seat portion of the upper web 6 30 of the tension member 3 is a spring plank 10 which is preferably formed with openings 11 therethrough for cooperative engagement with A. R. A. squaring lugs 12 formed on the upper surface of the spring 35 plank seat portion of the tension member. The spring plank 10 is preferably channel shape in cross section, as indicated particularly in Figure 1, and may be formed from a blank of standard width, the necessary increased width at the ends being secured by 40 decreasing the height of the upstanding side flanges at these points. In the embodiment illustrated, a frame is shown which, in general outline and size of the bolster opening, 45 corresponds with an A. R. A. seventy ton frame but it is obvious that our invention may be embodied in frames of any desired character. With such frames, five unit nests 50 of springs are usually employed and, in accordance with our invention, such standard five unit nests of springs or any nests of springs are increased in capacity, as more fully explained hereinafter.

Positioned on the spring plank 10 is a 55 spring plate 13 preferably provided, in the present embodiment, with five spring locating collars 14, said collars being normally positioned with respect to each other for receiving a standard five unit nest of 60 springs, each unit 15 preferably comprising an outer coil 16 and an inner coil 17, the inner coil 17 preferably snugly fitting around its corresponding collar 14 and the outer coil 16 preferably wound in the opposite manner and properly positioned by the

inner coil 17, a normal amount of clearance being provided therebetween. Although the five unit nest of springs is positioned so that the spring units are a normal distance apart, yet, in the embodiment shown, the nest as a 70 whole is positioned at an angle of ninety degrees with respect to the normal location of the A. R. A. standard five unit nest of springs, that is, the long axis of said nest of springs extends transversely rather than 75 longitudinally of the frame but the center of gravity thereof preferably lies directly over the longitudinal center line of said frame as well as over the longitudinal center line of the spring plank 10.

For increasing the spring capacity of the nest of springs, in the present embodiment, we provide an additional pair of springs 18 placed approximately on the longitudinal center line of the side frame and positioned 80 one on each side of the central spring unit of the five unit nest of springs. If, as is preferable, the outer diameter of the additional springs 18 corresponds with that of the spring units 15, said springs are preferably positioned with normal clearance with respect to the adjacent springs of the five unit nest of springs and, thereby, complete the formation of a hexagonal nest of springs, as shown most clearly in Figure 2, the long 85 axis of said hexagon extending longitudinally of the frame. For the purpose of receiving the extra units 18, the spring plate 13 is correspondingly extended and formed with spring positioning collars or bosses 19, 90 said bosses, in the present instance, being preferably extended upward a distance sufficiently great so that they may be formed with perforations 20 and serve for receiving retaining bolts 21 extending therethrough 95 and through correspondingly formed apertures 22 in the upper spring plate 23, whereby the adjacent portions of the perforated bosses on the spring plate extend sufficiently close together to enable the employment of 100 retaining bolts 21 short enough to obviate the necessity of perforating the spring plank 10 and web 6 of the tension member thereunder for receiving said retaining bolts upon compression of the springs. Because of 1 using the two retaining bolts 21 through the embossed portions of the spring plates, as illustrated, it is possible to dispense with the usual centrally positioned retaining bolt, but it may be desirable, however, to form 105 the usual central retaining bolt apertures 24 in the spring plank and 25 in the side frames so that the standard five unit nest of springs may be used interchangeably with the seven unit nest of springs, as shown, or may be 110 used for replacement purposes, if desired. The spring plates, as is usual, are preferably formed with substantially conical locating bosses 26 preferably formed for engagement 115 in the usual locating side frame apertures 120

27 and bolster apertures 28 normally located on the longitudinal center line of the side frame 1. If desired, the usual single embossment provided at each end of the spring 5 plank for limiting outward shifting of the nest of springs may be replaced by a pair of bosses 29 positioned as indicated in Figure 2 so as not to necessitate the undue lengthening of the spring plank. These 10 bosses, however, may be omitted, if desired, to make the arrangement interchangeable with the standard five unit nest of springs 15 normally positioned.

On account of the increased size of the 15 nest of springs in a direction transverse with respect to the side frame 1, not only is the spring plank increased in length but the bolster 30 is preferably correspondingly increased in length and the substantially horizontal portion or web 31 thereof is preferably extended inwardly, as shown in Figure 3, so as to provide just enough area for receiving the upper spring plate 23. On account of the increased dimension of the nest 25 of springs in a direction longitudinal of the side frame, it may be found desirable when using auxiliary springs 18 of a diameter corresponding with or greater than the spring units 15, to provide for sufficient clearance 30 with respect to the bolster guiding portions of the side frame by cutting away the lower portions of said guiding portions to a degree sufficient to just provide the necessary clearance. The upper web 6 of the tension member 35 35 may be of a width corresponding with or slightly less than the corresponding dimension of the nest of springs, and, in the present embodiment, said width is slightly less than the corresponding dimension of 40 the nest of springs, as indicated in Figure 4.

For efficiently supporting the individual spring units of the nest of springs, the front or outer web 8 is preferably sloped outward 45 and upward from the lower web 7 to meet the upper web 6 substantially directly beneath the two outermost spring units 15 and the inner web 9 is correspondingly sloped with respect to the innermost spring units 50 15. Between these spring units and the upright portions of the webs 8 and 9, said webs are preferably of gradually varying slope, as particularly shown in Figure 4. In order to form a spring plank seat portion of adequate width, the upper web 6 of the tension member is preferably extended beyond the upper ends of the sloping webs 8 and 9 to form extended flange or shelf portions 32- 55 and 33, respectively, said shelf portions extending at a maximum width beneath the outermost and innermost spring units 15 and tapering off in width at opposite sides of said spring units, as shown most clearly in Figures 2 and 4. For properly supporting 60 the center spring unit 15, transversely ex-

tending webs 34 are provided, said webs preferably extending between the webs 6 and 7 inwardly from the webs 8 and 9, respectively, to adjacent the aperture 25 in the web 6, if used. If no aperture 25 is provided, a continuous web may replace the web 34, which web then need not extend the full distance from the web 6 to the web 7 for its entire length. The auxiliary or additional spring units 18 may be efficiently supported by forming stools 35 preferably angular or + shape in cross section directly therebeneath between the webs 6 and 7 of the tension member. 70 75

The auxiliary springs 18 are, in the embodiment shown, of less free height than the original spring units 15 of the five unit nest of springs. Although the height of these springs may be varied within wide limits yet their free height is preferably such 80 that they are just engaged by the upper spring plate when the other springs are under normal load and the solid height of said auxiliary springs preferably corresponds with that of the other springs so that they 85 all go solid simultaneously. For that purpose, the auxiliary springs 18 are preferably formed of heavier stock and may be merely single coil springs, as illustrated, although, as will be obvious, the capacity of 90 said springs, when compressed solid, may correspond substantially with that of the other spring units because of the increased size of the material from which they are 95 formed. 100

Referring now to the embodiment of our invention illustrated in Figures 6 to 9, inclusive, a very similar arrangement is disclosed which differs from the aforescribed arrangement in the following particulars. 105 The standard five unit nest of springs 15^a is normally positioned, that is, the long axis thereof extends along the longitudinal axis of the side frame and the auxiliary or supplemental shorter springs 18^a are respectively disposed inwardly and outwardly of the center spring unit of the five unit nest of springs along the longitudinal center line of the spring plank rather than that of the side frame. If the retaining bolts for the 110 spring plates extended through these auxiliary springs 18^a spring plates substantially identical with those illustrated in Figure 5 might be used except that the locating bosses 26 thereof would be shifted 115 through an angle of ninety degrees so that they would extend perpendicular to the line between retaining bolt bosses rather than in line with said bosses. However, in the present embodiment, we prefer to use a single retaining bolt 21^a extending through the central spring unit 15^a of the standard five unit nest of springs and, as is obvious, said retaining bolt may be constructed and disposed in standard position and extend 120 125 130

through appropriately embossed portions 19^a in the spring plates. On account of this construction, the spring plank and associated side frame are necessarily formed with 5 bolt receiving apertures 24^a and 25^a, respectively as shown most clearly in Figures 8 and 9.

The auxiliary springs 18^a may be of a height and constructed of material corresponding with the springs 18 of the previous embodiment so that the capacity thereof is reserved until after a predetermined compression of the standard five unit nest of springs. It will be noted that the spring retaining collars 19^a in the upper spring plate 23^a are preferably sufficiently high or deep to prevent displacement of the auxiliary springs 18^a. The spring plank may be of standard width and correspondingly increased length and formed with the usual embossments for limiting outward shifting of the nest of springs replaced by a pair of embossments 29^a, positioned as indicated in Figure 7, although, if desired, said embossments or bosses may be omitted. The horizontal portion 31^a of the bolster which engages the upper spring plate 23^a is necessarily extended to a greater width locally to take care of the inner auxiliary spring unit 18^a, as shown particularly in Figure 8. The reinforcement of the upper web 6^a, at the spring plank seat portion thereof, may correspond substantially with that described in connection with that of the previous embodiment except that the webs 8^a and 9^a follow a slightly different line at their upper ends to correspond with the changed positioning of the hexagonally arranged springs thereabove. Inasmuch as only the center spring unit lies 40 on the longitudinal center line of the side frame, it becomes unnecessary to use stools corresponding to those designated by the reference character 35 of the previous embodiment. Except as specifically described in 45 connection with the present embodiment, the details thereof may correspond with those of the first embodiment.

By virtue of the foregoing construction, it will be apparent that we have devised a car truck in which the capacity of the springs supporting the bolster is increased, said capacity, however, preferably not coming into play until after the normal load has been applied on said bolster when the force of 50 the springs increases at a greater rate than previously. Although the arrangements shown are particularly adapted for seventy ton frames yet the principles there disclosed may be embodied in frames of any desired 55 capacity or character. Although the frames, bolsters and spring planks have been modified to correspond with the increased spring capacity yet, if desired, standard nests of 60 springs may be used interchangeably there-

with or for replacement purposes, if desired, as heretofore explained.

Having now described our invention, we claim:

1. In a car truck, in combination, a side frame formed with a bolster opening and a spring plank seat portion underlying said opening, a nest of springs supported by said spring plank seat portion, a bolster supported by said nest of springs, and additional springs of approximately the same diameter positioned one on either side of said nest, the springs in said nest being longer than the additional springs whereby the latter are not stressed until after a predetermined compression of said nest of springs. 80

2. In a car truck, in combination, a side frame formed with a bolster opening and a spring plank seat portion beneath said opening, a nest of spring units supported by said spring plank seat portion, and a bolster supported by said nest of springs, and an additional spring of a capacity approximating that of one of the units of the nest of springs positioned adjacent the nest of springs, said additional spring being shorter than said nest of springs whereby no compression thereof occurs until after a predetermined deflection of the nest of springs, said springs being so proportioned that they are all 90 adapted to go solid simultaneously. 95

3. In a car truck, in combination, a side frame formed with a bolster opening and a spring plank seat portion underlying said opening, a nest of springs supported by said spring plank seat portion, and a plurality 100 of extra springs arranged on opposite sides of said nest of springs and of a diameter approximating that of the first-mentioned springs, said extra springs being shorter than the other springs whereby they are 105 not brought into play until after a predetermined compression of said other springs.

4. In a car truck, in combination, a side frame formed with a bolster opening and a spring supporting portion underlying said 110 opening, a five unit nest of springs supported by said portion, and a bolster supported by said nest of springs, said nest of springs being positioned in standard relation with respect to each other and a pair of 115 springs positioned one on either side of the center spring unit of said nest of springs, said pair of springs being of a shorter free length than the springs of said nest of springs, whereby they are not engaged by the bolster until a predetermined deflection 120 thereof.

5. In a car truck, in combination, a side frame formed with a bolster opening and a spring supporting seat portion beneath said opening, a five unit nest of springs supported 125 by said portion and arranged in standard position with respect to each other and a

bolster supported by said nest of springs, said spring capacity being reinforced by a pair of springs positioned on the short axis of said nest of springs, one spring on either side of the center spring unit thereof, said springs being of a shorter free length than those of the five unit nest of springs and being constructed of thicker material whereby they are adapted to go solid simultaneously with the springs of the five unit nest of springs.

6. In a car truck, in combination, a side frame comprising a compression member, a tension member, bolster guide columns spacing intermediate portions of said members and leaving a window opening therebetween, that portion of the tension member, beneath the window opening, serving as a spring plank seat portion, a spring plank supported on said spring plank seat portion, a spring plate supported on said spring plank and formed with means for positioning the same with respect to said spring plank and means for properly locating associated springs with respect thereto, a standard five unit nest of springs supported on said spring plate, a second spring plate supported on said nest of springs and in turn supporting a bolster thereabove, the capacity of said nest of springs being reinforced by additional springs positioned on opposite sides of the center spring unit of said nest of springs, said additional springs being of a shorter free height than the springs of the five unit nest of springs but of a solid height corresponding therewith, the spring plates being correspondingly extended for receiving said additional springs and retaining means extending between said spring plates.

7. In a car truck, in combination, a side frame formed with a bolster opening and a spring supporting portion underlying said opening, a seven unit nest of springs supported by said portion and disposed with six of said spring units forming a hexagon and the other spring unit centrally disposed with respect thereto, two oppositely disposed spring units of said hexagon being formed of shorter free height than the remaining spring units whereby they are adapted for coming into action only after a predetermined compression of the other spring units, all of said spring units being adapted for the support of a bolster positioned thereabove.

8. In a car truck, in combination, a side frame formed with a bolster opening and a spring plank seat portion beneath said opening, a seven unit nest of springs supported by said spring plank seat portion and a bolster supported by said nest of springs, six of the spring units of said nest of springs being hexagonally disposed and the seventh spring unit being centrally arranged with respect thereto, one pair of said spring units

being of a shorter free height than the other spring units whereby the capacity thereof is reserved until a predetermined deflection of the supported bolster.

9. In a car truck, in combination, a side frame formed with a compression member, a tension member and bolster guide columns spacing intermediate portions of said members leaving a window opening therebetween, that portion of the tension member, beneath the window opening, being laterally widened to serve for the support of the bolster springs, a nest of springs supported by said widened portion and formed as a hexagon in outline, two of the hexagon-forming oppositely-disposed spring units being of less free height than that of the remaining spring units whereby the capacity thereof is reserved until after a predetermined compression of said other spring units, said shorter spring units, however, being formed of thicker material whereby they are stronger than the other spring units and adapted to go solid substantially simultaneously with the other spring units.

10. In a car truck, in combination, a side frame comprising a compression member, a tension member and bolster guide columns spacing intermediate portions of said members leaving a window opening therebetween, that portion of the tension member, beneath the window opening, being substantially box shape in cross section with the upper web thereof laterally widened to form a spring plank seat portion for the support of a seven unit nest of springs hexagonally arranged with one of said spring units centrally positioned, the side webs of said box section, for the purpose of efficiently supporting said springs, being sloped outwardly and upwardly directly beneath the innermost and outermost springs and the center spring unit of said nest of springs being supported by transverse webs extending between the side webs and upper and lower webs but discontinued short of the longitudinal center line of the frame.

11. In a truck, in combination, a side frame formed with a bolster opening and a spring supporting portion underlying said opening, a plurality of springs of approximately the same diameter supported by said portion, and a bolster supported by said springs, certain of the springs being diagonally arranged on opposite sides of, and shorter than, the main group of said springs whereby they are not stressed until after a predetermined compression of said main group.

12. In a car truck, in combination, a side frame formed with a bolster opening and a spring supporting portion beneath said opening, a nest of springs supported by said spring supporting portion, and a bolster supported by said nest of springs, a certain

- proportion of the nest of springs being shorter than the remainder of said nest of springs whereby no compression thereof occurs until after a predetermined deflection of the remainder of said nest of springs, said springs being so proportioned that the shorter springs are just engaged by the bolster when the other springs are normally loaded.
- 10 13. In a car truck, in combination, a side frame formed with a bolster opening and a spring plank seat portion underlying said opening, a nest of springs supported by said spring plank seat portion, and a plurality of extra springs arranged on opposite sides of said nest of springs, said extra springs being shorter than the other springs whereby they are not brought into play until after said other springs are normally loaded.
- 15 14. In a car truck, in combination, a side frame formed with a bolster opening and a spring supporting seat portion beneath said opening, a five unit nest of springs supported by said portion and arranged in standard position with respect to each other and a bolster supported by said nest of springs, said spring capacity being reinforced by a pair of springs positioned on the short axis of said nest of springs, one
- 20 30 spring on either side of the center spring unit thereof, said springs being of a shorter free length than those of the five unit nest of springs.
- 15 35 In a car truck, in combination, a side frame comprising a compression member, a tension member, bolster guide columns spacing intermediate portions of said members and leaving a window opening therebetween, that portion of the tension member, beneath the window opening, serving as a spring plank seat portion, a spring plank supported on said spring plank seat portion, a spring plate supported on said spring plank and formed with means for positioning the same
- 40 45 with respect to said spring plank and means for properly locating associated springs with respect thereto, a standard five unit nest of springs supported on said spring plate, a second spring plate supported on said nest of springs and in turn supporting a bolster thereabove, the capacity of said nest of springs being reinforced by additional springs positioned on opposite sides of the center spring unit of said nest of springs, said additional springs being of a shorter free height than the springs of the five unit nest of springs.
- 16 50 55 In a car truck, in combination, a side frame formed with a compression member, a tension member and bolster guide columns spacing intermediate portions of said members leaving a window opening therebetween, that portion of the tension member, beneath the window opening, being laterally widened to serve for the support of the bolster springs, a nest of springs supported by said widened portion and formed as a hexagon in outline, two of the hexagon-forming oppositely-disposed spring units being of less free height than that of the remaining spring units whereby the capacity thereof is reserved until after a predetermined compression of said other spring units.
- 17 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

tions of the upper web, said side webs being normally upright but sloped outwardly and upwardly beneath the portion of the frame for supporting the nest of springs whereby
5 the upper edges of said side webs engage the upper web directly beneath the outer and inner springs of said nest of springs, said upper web being additionally reinforced beneath the central spring unit by transverse
10 webs extending between the upper and lower webs and inwardly toward each other from the side webs.

20. A spring plate for a nest of springs formed with five spring locating means posi-

tioned for properly spacing the five double 15 coil spring units of a standard five unit nest of springs and spring locating embossments positioned one on either side of the central spring positioning means for the nest of springs, said latter means being adapted for 20 properly positioning extra single coil springs and apertured for the reception of retaining means.

In testimony whereof we affix our signatures.
